UNITED STATES PATENT OFFICE.

FRED WESLEY COOK, OF NORTH CHICAGO, ILLINOIS, ASSIGNOR TO CHICAGO HARDWARE FOUNDRY COMPANY, OF NORTH CHICAGO, ILLINOIS, A CORPORATION OF ILLINOIS.

DESIGN FOR A STOOL PEDESTAL.

Application filed February 14, 1924. Serial No. 8,638. Term of patent 14 years.

To all whom it may concern:

Be it known that I, FRED WESLEY COOK, a citizen of the United States of America, residing at North Chicago, in the county of Lake and State of Illinois, have invented a new, original, and ornamental Design for Stool Pedestals, of which the following is a specification, reference being had to the accompanying drawing, forming a part thereof.

The figure is a perspective view of a stool pedestal, showing my new design.

I claim:

The ornamental design for a stool pedestal, as shown.

FRED WESLEY COOK.
